ENGINE EXHAUST SYSTEM

Ray T. Flugger, 2055 Hatch Road,
Novato, Calif. 94947

Filed Oct. 9, 1967, Ser. No. 8,922

Term of patent 14 years

Int. Cl. D12—14, 08; D15—01

U.S. Cl. D14—6

FIG. 1.

FIG. 2.

FIG. 1 is a top plan view of an exhaust system illustrating my new design; and
FIG. 2 is a front elevational view of my new design.
I claim:
The ornamental design for an engine exhaust system, substantially as shown.
